DESIGN FOR A COOKIE JAR

Frances Poe, Wilmette, Ill.

Application November 1, 1943, Serial No. 111,569

Term of patent 7 years

(Cl. 58—25)

To all whom it may concern:

Be it known that I, Frances Poe, a citizen of the United States, residing at Wilmette, in the county of Cook and State of Illinois, have invented a new, original, and ornamental Design for a Cookie Jar, of which the following is a specification, reference being had to the accompanying drawing, forming part thereof.

I claim:

The ornamental design for a cookie jar, substantially as shown.

FRANCES POE.
